UNITED STATES PATENT OFFICE.

ARTHUR E. PETERS, OF LITTLETON, COLORADO, ASSIGNOR TO INGERSOLL-RAND COMPANY, OF JERSEY CITY, NEW JERSEY, A CORPORATION OF NEW JERSEY.

ENGINE.

Application filed April 16, 1926. Serial No. 102,495.

This invention relates to fluid actuated engines, and more particularly to that type of engine in which the piston is adapted to rotate with a crank, as for instance, in the 5 square piston type of engine.

It is an object of the invention to distribute the motive fluid for actuating the piston in an efficient manner. A further object of the invention is to reduce the clearance 10 volume of the piston within its cylinder and to provide cut-off whereby the expansive force of the motive fluid may be utilized.

Further objects will be in part obvious and in part pointed out hereinafter.

15 In the drawings in which similar reference characters refer to similar parts,

Figure 1 is a plan view, partly in section, of an engine constructed in accordance with the practice of the invention,

20 Figure 2 is a cross section taken along the line 2—2 of Figure 1 looking in the direction of the arrows, portions being broken away to show the interior construction of the pistons and their valves,

25 Figure 3 is a cross section taken along the line 2—2 of Figure 1 looking in the direction of the arrows, the driving gears being indicated in dotted lines, and

30 Figures 4, 5 and 6 are views partly diagrammatic showing the operation of the distributing valves and the exhaust ports at important points in their cycle of operations.

Referring to the drawings, the motor comprises a cylinder A held between a front 35 head B and a back head C. A pair of crank shafts D extend through the back head C into the cylinder A and terminate in crank pins E upon which are journaled as by means of anti-friction bearings F, a pair of rectangular 40 rotary pistons G. Each of the pistons G is provided with a rectangular frame H which is adapted to reciprocate in the cylinder A as the crank shafts D rotate. The pistons G are slidably mounted within the rectangular 45 frames H as a guide and adapted to rotate with respect to the crank pins E.

The pistons G are of a type in which there is provided a hollow space which is maintained filled with motive fluid to be distributed to the pressure faces J and K of the pistons for causing the said pistons to reciprocate within the frames H to produce rotation of the cranks D. Means is provided for distributing such motive fluid to the pressure faces J and K which in this instance in-

cludes a cylindrical hollow valve L adapted to rotate with the crank pin E in a cylindrical bore O formed concentrically with the crank pin E. The valve is provided with a port P which as the valve rotates registers successively with ports Q and R leading from the cylindrical bore O to the pressure faces J and K respectively of the piston G. Valves L are keyed to sleeves S on the crank pins E and are free to move longitudinally with respect to the crank pins E and also bear on the pistons G independently of the crank pins E. The outer faces T of the valves L are adapted to slide on the front cylinder head B and are provided with apertures U in communication with a supply port V in the front cylinder head B.

The unbalanced pressure within the cylindrical valve L due to the size of the port U is counter-balanced by a disk comprising a 75 cup leather W supported by the bushing S and adapted to seal a central bore X of the valve L from leakage. A bolt Z bearing against a plate Y holds the cup leather W on the crank pin E. Proper balance of the pressures against the outer face T of the valve L is obtained by providing a second opening b in that face.

The crank shafts D are journaled by means of anti-friction bearings c in the rear face of 85 the back head C and also by means of the anti-friction bearings d suitably mounted in a flange e attached to the back head C by means of suitable bolts f. A chamber g is preferably provided in the back head C to 90 accommodate weights h suitably bolted or keyed to the crank shafts D and adapted to counterbalance the weight of the rotating pistons L. Each shaft D is provided with a driving gear j meshing with a main gear k mounted on the main shaft o suitably journaled by means of anti-friction bearings p in the flange e.

The supply of motive fluid to the pistons L may be obtained through a supply pipe 100 q attached to a supply chamber r in a valve chest s mounted on the front cylinder head B. Preferably the valve chest s is bored longitudinally and provided with ring grooves t, u, v, w and x through which the 105 motive fluid and exhaust are adapted to pass. The ring grooves t and x are connected with the port V and also by means of longitudinal bores y with the grooves v and w respectively. The groove u communicates with a 110

clutch mechanism not described or shown in the drawing since it does not form part of the invention claimed. The bore of the valve chest *s* is provided with a removable sleeve *z* having perforations 4 communicating with the grooves *t*, *u*, *v*, *w*, and *x* respectively.

A throttle valve 3 is adapted to slide longitudinally within the sleeve *z* and is provided with perforations 2 adapted to register with the perforations 4 in operative positions of the valve 3. The valve 3 is hollow and is adapted to receive live motive fluid from the groove *r* through the perforations 4 and 2 into its interior. In operative position of the valve 3, motive fluid is adapted to be admitted to the grooves *v* and *w* through the perforations 2 and 4 and thence to operate the pistons *G* through the ports *U* and *V*. The valve 3 is adapted to be actuated by means of a throttle lever 5 provided with a pinion (not shown) meshing with a rack 6 formed integrally with the end of the valve 3. The ends of the bore of the valve chest *s* are closed by means of suitable plugs 7 held in place by pins 8 passing through the valve chest *s* and are bored to receive coil springs 9 bearing against the ends of the valve 3 to hold the latter in a neutral position. In its uppermost position as shown in Figure 1, the valve 3 is adapted to permit motive fluid to flow to the ring groove *u* for operating the clutch (not shown), at the same position motive fluid is admitted to operate the pistons *G*. In its lowermost position, the end of the valve 3 uncovers the perforations 2 connecting with the ring groove *u* and allows motive fluid to exhaust from said ring groove through a hole 10 in the plug 7 to atmosphere. In the neutral position of the valve 3 compressed motive fluid is permitted to escape from the ring groove *x* through perforations 11 in the sleeve *z* and through a cooperating passage 12 in the body of the valve 3 and a longitudinal bore 13 in the valve to atmosphere through a bore 14 in the plug 7.

In this embodiment the motor is adapted to operate a hoist comprising a gear box 15 containing reduction gears (not shown) adapted to be driven by the shaft *o* for operating selectively a pair of drums 16 and 17 concentric with the drive shaft *o*. The drum 17 is mounted on a center bearing or sleeve 18 attached as by means of a pin 19 to the flange *e* at one end and to the gear box 15 at the other end. The drum 16 is adapted to rotate on an extension (not shown) of the drum 17. A suitable automatic clutch (not shown) disposed within the gear box 15 is adapted to connect the drums 16 and 17 with the drive shaft *o*. A suitable cage 20 is attached by means of bolts 21 to the rear cylinder head *C* of the motor and to the gear box 15. The cage 20 is provided with arms 21 extending longitudinally of the hoist, there being openings between the arms 21 to permit ropes 22

to pass through from the drums 16 and 17. The gear box 15 is provided with a cover 23 attached by means of bolts 24 and permits access to the reduction gearing and clutch housed within.

The operation of the motor and more particularly of the valve *L* is shown more clearly in Figures 4, 5, and 6. Each piston *G* is provided with ports *Q* and *R* in communication with a pressure face of the piston *G*. The valve *L* is adapted by means of its port *P* to supply motive fluid through the ports *Q* and *R* to operate the piston. For exhausting motive fluid from the cylinder *A* there are provided grooves 25 formed in both cylinder heads *B* and *C* which are adapted to be uncovered by the frames *H* as they reciprocate, and the timing of the opening of the grooves 25 to the space within the frames *H* is adjusted by the size and position of the grooves 25.

Referring to Figure 4 and considering the piston *G* at the left, the piston is shown in its uppermost position at which point the port *P* of the valve *T* has come into communication with the upper port *Q* in the piston *G*. Motive fluid entering as indicated by the arrow forces the piston *G* downwardly rotating the crank *E* and therefore turning the valve *T*. As the piston *G* descends to the position shown in Figure 5, the port *P* passes out of communication with the port *Q* cutting off the supply of motive fluid at approximately five eighths of the stroke and permitting expansion of the motive fluid beyond this point to the point shown in Figure 6. Motive fluid is permitted to escape through the upper left hand grooves 25 in the cylinder heads *B* and *C* to atmosphere. During the upward portion of the stroke of the piston *G*, the cycle of operations is similar with respect to the lower port *R* of the piston *G* and the port *P* in the valve *T*. The opposite face of the piston *G* is in communication with atmosphere through the exhaust port groove 25 during the entire upward stroke since the frame *H* is moving toward the left (Figure 6) and does not close the groove 25 until reaching approximately upward dead center. It will be noted that the ports *U* and *V* are constantly in line with the center of rotation of the crank shaft *D*, thus permitting motive fluid to fill the space within the valve *T* at all times that the throttle valve is in an operative position.

The two pistons *G* are set at 90° so that there is no dead center point and the torque on the drive shaft *o* is uniform.

Thus by the above construction are accomplished among others, the objects hereinbefore referred to.

I claim:

1. A fluid actuated engine comprising a cylinder; a crank shaft having a crank pin extending into the cylinder; a rotary piston journaled on said crank pin and adapted to

rotate therewith, and a valve coupled to said pin and journaled in said piston independently of the pin for distributing motive fluid to the pressure faces of said piston.

- 5 2. A fluid actuated engine comprising a cylinder; a crank shaft having a crank pin extending into the cylinder; a frame adapted to reciprocate in the cylinder; a piston journaled on the crank pin adapted to rotate thereon and reciprocate the frame, and a valve coupled to said pin and journaled in said piston, independently of the pin, for distributing motive fluid to the pressure faces of said piston.
- 10 3. A fluid actuated engine comprising a cylinder; a crank shaft having a crank pin extending into the cylinder; a hollow rectangular rotary piston journaled on said crank pin and adapted to rotate therewith; a frame adapted to reciprocate in the cylinder and be actuated by the piston, and a valve coupled to said pin and journaled in said piston, independently of the pin, for distributing motive fluid to the pressure faces
- 25 of said piston.

4. A fluid actuated engine comprising a cylinder; a crank shaft having a crank pin extending into the cylinder; a hollow rectangular piston journaled on the crank pin and adapted to rotate thereon, and provided with a cylindrical bore and ports leading to

the pressure faces of the piston, and a valve coupled to said pin and journaled in the piston independently of the pin for distributing motive fluid to the pressure faces to the 35 piston.

5. A fluid actuated engine comprising a cylinder; a crank shaft having a crank pin extending into the cylinder; a frame adapted to reciprocate in the cylinder; a rectangular 40 piston journaled on the crank pin, and adapted to rotate thereon, and having a cylindrical bore and a port communicating therefrom to the pressure faces of the piston, said piston being arranged to reciprocate within said 45 frame, and a cylindrical valve independently journaled within the bore of the piston coupled to the pin for distributing motive fluid to the pressure faces of the piston.

6. A fluid actuated engine comprising a 50 cylinder; a crank shaft having a crank pin extending into the cylinder; a rotary piston journaled on said crank pin and adapted to rotate therewith and a valve in said piston for distributing motive fluid to the pressure faces of said piston, said valve and said piston being concentrically and independently mounted on said crank pin.

In testimony whereof I have signed this specification.

ARTHUR E. PETERS.
